Attorney

UNITED STATES PATENT OFFICE

JOHN H. SMITH, OF BOLINDALE, MASSACHUSETTS

SOUND-PRODUCING DANCING SHOE

Application filed June 4, 1929. Serial No. 368,420.

The present invention appertains to new and useful improvements in amusement devices and more particularly to a noise producing dancing shoe.

The invention briefly consists in providing dancing shoes with electrical sound producing devices suitably mounted thereon and electrically connected through a switch to a suitable current supply source, so that by actuating the switch at various rhythmic dance movements of the feet, the sound producing device will produce a sound, with the end in view of increasing the entertaining effect of the dance.

An important object of the invention is to provide a dancing shoe with a noise producing device which can be sounded at predetermined intervals at the discretion of the dancer.

Other and important advantages of the invention will become more apparent to the reader after considering the invention as described and claimed hereinafter.

In the drawing:

Figure 1 represents a side elevation of dancing shoe equipped with the novel sound producing means.

Figure 2 represents an enlarged fragmentary longitudinal sectional view through the shoe showing the switch means employed.

Figure 3 represents a fragmentary sectional view through the heel portion of the dancing shoe showing the electrical socket carried thereby and also showing in side elevation a corded plug extending from a current supply source.

Figure 4 represents a diagrammatic view disclosing additional supply of current and the switch and sound producing device on the shoe and constructed with the current supply cord.

In the drawings wherein like numerals designate like parts, it will be seen that the present invention is applicable to a dancing shoe which is referred to the drawings by numeral 5. An electric socket structure 6 is mounted within a cavity 7 in the heel of the shoe and from the socket 6 extends the wires 8 and 9. These wires are disposed between the inner sole 10 and the outer sole

11 of the shoe structure and is preferably embedded within the usual filler substance 12.

A pair of contacts 13 and 14 are exposed through the top surface of the inner sole 10. These contacts are interposed in the conductor 8 and a spring arm 15 secured at one end to one of the contacts (preferably to contact 14) adapted to contact at its free end with the other contact when pressure is exerted against the same by the foot of the dancer.

In this manner a circuit is completed through the sound producing device 16, preferably mounted upon the toe of the shoe, as substantially shown in Figure 1. This sound producing device may be in the form of a magnetic bell, or in fact any other suitable electroresponsive device capable of producing a sound suitable for the purpose.

In Figure 3 the cord 17 has a plug 18 of the usual construction secured at one end while its opposite end is connected to the current supply source. Obviously when a dancer is about to commence his performance, he will insert the plug into the socket 6. The cord 17 may be of a suitable length so that its activity may carry him over the desired area without liability of the plug pulling loose.

It is to be understood that various changes in the shape, size, materials may be resorted to in the production of this novel dancing shoe, without departing from the spirit and scope of the invention as claimed hereinafter.

Having thus described the invention, what I claim as new and desire to secure by Letters Patent is:

1. A dancing shoe comprising an electrical sound producing device mounted upon the shoe, and electrical socket in the heel of the shoe, a spring switch mounted upon the inner sole of the shoe adjacent the forward end thereof, and an electrical connection between the socket, the switch and the said sound producing device, said switch adapted to be engaged by the toe of the wearer of the shoe for closing the same.

2. A dancing shoe of the character de-

scribed comprising an electric circuit in said shoe, an electrically actuated sound producing device mounted on the shoe and interposed in the circuit and a circuit closing switch interposed in the circuit within the 5 forward end portion of the shoe comprising a pair of spaced contacts, a spring arm fixed to one of the contacts and extending adjacent the other contact and normally disengaged therefrom, said arm adapted to be 10 engaged by the toe of the wearer of the shoe in a manner to close the switch.

In testimony whereof I affix my signature.

JOHN H. SMITH.
